PLASTIC SHOE DISPLAY FORM

Stanley Nettler, Great Neck, and Mario Maccaferri, Rye, N. Y.; said Maccaferri assignor to said Nettler

Application January 26, 1951, Serial No. 208,008

2 Claims. (Cl. 12—128)

1

This invention relates to plastic shoe display forms; and the nature and objects of the invention will be readily recognized and understood by those skilled in the arts involved in the light of the following detailed description and explanation of the accompanying drawings illustrating what we now believe to be the preferred embodiments or structural and mechanical expressions of a plastic shoe form and of apparatus for producing the same, from among various other embodiments, structural and mechanical expressions, forms, arrangements, designs and combinations of which the invention is capable and adapted within the broad spirit and scope thereof.

Plastic forms for the display of shoes have been in use for a number of years. Such a plastic form is characterized generally as a hollow, relatively thin-walled reproduction in simulation of the human foot and ankle, either the right or the left foot and ankle. They are sold in pairs comprised of a right and left shoe form for insertion in a pair of shoes of the size or limited range of sizes for which a particular pair of forms is designed and dimensioned. Each form is an accurate reproduction in dimensions and in external contours or shape of a human foot or ankle of a definite size corresponding to a size, or limited range of sizes, of the standard system of shoe sizes. The forms are insertable, preferably under some degree of compression, into the shoes of the proper sizes so as to maintain the shape of the shoes and realistically and artistically display the shoes as they will appear on the feet of a wearer in use. Such a hollow, thin-walled plastic form is constructed to be open at the bottom with a surrounding, inturned flange therearound carrying out the contours around the bottom of the foot and the outer portions of and around the sole of the foot. Such flange forms a support corresponding to the sole of a foot for engagement with the inner sole of the shoe in which the form is inserted for display. Due to the thin-walled structure and the characteristics of the plastic of which formed, together with the open bottom, such a shoe form has a degree of resiliency and is laterally bendable or compressible from the opposite sides, so that, when inserted in a shoe of the size for which the form is designed, the form will tend to expand and hold the shoe in the desired stretched or on-the-foot shape for effective display.

All of the types of plastic shoe forms now on the market with which we are familiar, are constructed of a plurality of parts or components which are bonded, cemented or otherwise secured together into assembled relation to provide the

2

completed shoe form of composite construction, as an accurate reproduction in size and external contours or shape of a human foot and ankle. One of such types of plastic shoe display forms now widely marketed and used, is comprised of two (2) parts or halves which are complementary, that is, one part forms the inner half (½) section and the other part the outer half (½) section of the foot and ankle, with these parts being joined together along their inner, mating edges to result in a joint or seam which passes or extends along the center of the front, top and back or heel of the form, that is, completely around the form. The joining of the two parts or halves of this type of form is effected by cementing, or by bonding by softening, the mating edges of the halves, with or without the aid of interengaging structural portions of the halves or sections. However, it has been found that whatever the method or manner of joining together the two parts or halves of the form may be, there always results a visible joint or seam at and along the area of the line of jointure between the halves which is unsightly and detracts materially from the appearance and display effectiveness of the form. Because of such joint or seam, the use of transparent plastic materials for these forms has not been practical or satisfactory to the trade, so that, the forms have been restricted for their construction to the use of non-transparent or opaque plastic materials in an effort to lower the visibility and minimize the unsightly effect of the joint or seam.

In addition to the unsightly appearance of the visible seam or joint in such a two or multiple-part plastic form, there are certain structural disadvantages inherent in such construction which tend to reduce the effective useful life of the form. In use the joints formed between the bonded or cemented parts of the form are subjected to forces developed by the compressing or bending of the form to place it under tension in inserted position in a shoe and by the expansion of the compressed form to its non-compressed position upon removal of the form from a shoe. The cumulative effect of such forces over a period of use tends to cause a seam or joint to open up, separate or crack, and once such separation is initiated or takes place at one point then continued use may cause aggravated or extended separation to a degree such as to render the form ineffective or unfit for further use. Further, these plastic display forms are subjected in use to various heat conditions resulting from the effect of the sun or intense display lighting, particularly where the forms are in shoes placed in display or

show windows. These heat conditions have a tendency to weaken or loosen the cemented or bonded joint and thus make separation thereof easier. Another disadvantage of the two piece or multiple-part plastic shoe form is the relatively high cost of production resulting from the necessity of separately molding the parts, then assembling the parts and cementing or bonding them together into the completed form, and finally performing a necessary finishing operation along the area of the seam or joint to minimize as much as possible the visibility of the joint or seam in the completed form.

It is a primary object of our present invention to overcome and substantially eliminate the foregoing difficulties and disadvantages inherent in the multiple-piece type of plastic shoe display form in which the parts of the form are cemented or bonded together, by providing a design and construction of one-piece, seamless, thin-walled, hollow and resilient plastic shoe form.

Another object is to provide such a one-piece plastic shoe form which may be produced by injection molding from a suitable thermoplastic material.

Another object is to provide such a shoe form which can be formed of transparent plastic material, either clear or colored, for effective shoe display, and which if desired may be readily illuminated due to its one-piece, seamless character to thereby more effectively display a shoe in which mounted.

A further object is to provide a design and construction of such a plastic shoe form in which the generally inwardly turned flange surrounding the bottom opening of the form may have a minimum width to maintain a maximum width of opening without substantially lessening the strength structurally or the inherent resiliency of the form.

A further object is to provide such form with a closed top integral with the walls of the form and without mold marks of any kind on the outer, top surface thereof.

Another object is to provide such a one-piece seamless plastic shoe form of a design and construction by which a simple form of expansion spring member may be readily inserted and seated in and around the forward portion of the form in position housed and releasably engaged within the adjacent portion of the flange surrounding the bottom opening in the form, for the purpose of restoring the form to its normal non-compressed shape after removal from compressed position in a shoe.

With the foregoing and various other objects, features and results in view, which others will be readily apparent from the following description and explanation, our invention consists in certain novel features in design and construction and in combinations of parts and elements, all as will be more fully referred to and specified hereinafter.

Referring to the accompanying drawings, in which similar reference characters refer to corresponding parts and elements throughout the figures thereof;

Fig. 9 is a transverse section taken as on line 9—9 of Fig. 3.

Fig. 9a is a perspective view of the spring unit for removable mounting in the form of Fig. 1.

We happen to have selected and to have disclosed herein as an example of our invention, a one-piece, seamless, plastic display shoe form of the so-called low heel type designed and intended for use in displaying shoes of the low heel classifications or styles. Such a low heel type of shoe display form of our invention is characterized generally by the fact that with the form in inserted position in a shoe, the lower exterior surface of the form at the under side of the heel portion thereof either lies in the same plane which passes through the lower surface of the form at the under side of the portion thereof representing the ball of a foot, or in a plane spaced a relatively slight distance above the plane at the under side of such ball portion. Our invention, however, is not limited to such low heel types of shoe display forms but includes and is embodied in forms of those types adapted for displaying shoes in the so-called medium heel and high heel ranges, respectively, in which the plane of the lower exterior surface of a form at the under side of the heel portion thereof is in a plane spaced at a substantial distance above the plane of the under exterior surface of the form beneath the ball portion thereof.

The example shoe form F of the low heel type embodying our invention is illustrated in Figs. 1 to 9 of the accompanying drawings, and typifies the various other types, styles, classes and sizes of shoe forms of the invention. The display form F is, in accordance with our invention, formed as a one-piece, seamless and hollow plastic structure having relatively thin walls throughout and being resilient so as to be bendable or compressible laterally, particularly at the ball portion of the form, for insertion of the form under at least slight compression into the shoe to be displayed. The shoe form F of the illustrated example is constructed of a cellulose acetate thermoplastic and is of a design and construction by which the form may be made by a single injection step in injection molding apparatus forming a part of our invention and disclosed and described in detail hereinafter. The shoe form F is designed as a relatively accurate replica or reproduction in dimensions and in external contours of a human foot and ankle. In this instance we happen to show the form F as a reproduction of the right foot and ankle, and of a size or dimensions such as to be insertable under compression in shoes of a definite size or limited range of sizes of the standard system of shoe sizes.

The shoe form F, which is a reproduction in dimensions and contour of a selected size of foot and ankle, comprises the sole portion S, the heel portion H, the ankle portion A, the ball portion B, the instep portion I and the toe portion T.

The ankle portion of the form F, which is designated generally by the reference character A, usually includes a relatively accurate reproduction in contour and dimensions of the ankle at

the ankle joint and of a portion of the ankle above the joint. Such upper portion of the ankle is designated generally by the reference character A' and terminates at its upper, outer end in the completely closed integral, flat top wall 10 which constitutes the top wall of the shoe form F.

The wall structure which makes up and constitutes the hollow shoe form F includes the outer side wall 20 which extends from the back wall 21 and merges into and with the wall 22 forming the toe portion T, and the inner side wall 23 which extends rearwardly from wall 22 to and merges with the back or rear wall 21. These walls are integral and continuous over and around the form and include the front wall 25 which extends upwardly over and defines the ball portion B, instep portion I, and the front of the upper ankle portion A', and which merges with the adjacent walls. The side, front and rear walls as above identified, join integrally with the top wall 10 at the upper side of ankle portion A'. There is thus provided an unbroken, smooth wall structure which is without seams or joints at any location thereon. The front of the form F is completely without joints or other visible seam forming construction along the central area thereof from the tip of the toe portion of the form to the top wall 10. This is the area of the surface of the form on which any joint, seams or other blemishes are most noticeable when a form is in display position in a shoe.

The top wall 10 is integral with the side walls 20 and 23, the front walls 22 and 25, and the rear wall 21, which walls join and merge therewith, so that there is no joint or seam around and between top wall 10 and the walls joined therewith. This top wall 10 in accordance with a feature of our invention, presents a plane outer surface which is completely smooth and without blemishes, marks or disfiguration of any kind. In the usual display position of the form F in a shoe, this top, closing wall 10 of the form is in position completely visible to an observer so that any marks or blemishes which may be visible thereon detract materially from the appearance and display effectiveness of the shoe form. The construction of top wall 10 as an integral molded component of the wall structure making up the form is an important feature of our invention.

The toe portion which is designated generally by the reference character T preferably includes longitudinally disposed, toe-forming grooves 11 formed in wall 22 to indicate at least some of the middle toes 12 of the foot. These toe-forming grooves 11 in the example form F which is for the right shoe, start with the innermost of the grooves being located approximately along the center line of instep portion I to thus form on the wall 22 of toe portion T a central rib 15. The side of the toe portion T to the right of grooves 11 generally simulates the big toe of the foot. The example shoe form F is primarily designed for use in displaying women's shoes and the main purpose of the toe forming grooves 11 and of locating these toe simulations at the middle section of the toe portion T, is to permit of applying to the simulated toes a suitable coloring to give the appearance of painted toe nails which will be visible with open toe shoes and thus add to the realistic and artistic appearance of the display. A transversely disposed groove 16 may be provided in wall 22 across the grooves 11 to simulate toe nails.

The lower, bottom or underside of the hollow,

thin walled shoe form F is open and is surrounded by the sole portion generally designated by the reference character S. This sole portion S is constituted by an inturned, transversely curved flange 30 which extends in this example as a continuous unbroken flange varying in width and in radii of curvature along different portions of its length at specific locations around the lower or bottom side of the form. This flange structure 30 which is integral with the walls of the form constitutes the sole portion S by which the form is supported and maintained in inserted position in a shoe with such flange 30 being engaged down on and against the usual inner sole of a shoe to be displayed.

The rearwardly or outwardly curved or convex heel section 31 of flange 30 which extends across and forms the under or sole portion of heel H is formed as an integral part and continuation of the rear wall 21 of the form F. The heel section 31 continues forwardly along and integral with the outer and inner side walls 20 and 23 as integral portions of these walls to provide the inner side flange section 32 and the outer side flange section 33. Flange sections 32 and 33 are of approximately the same radius of curvature inwardly and are of substantially equal width but with the flange section 32 being extended forwardly a greater distance along the wall 23 than the distance the flange section 33 is extended along wall 20. Outer side flange section 33 terminates at a location generally below the front of the upper ankle section A', while the inner side section 32 extends a distance forwardly to terminate approximately at the rear of the ball portion B. The flange sections 32 and 33 are continued forwardly along the inner and outer sides of the shoe form, as flange sections 34 and 35 which extend to the tip of the toe portion T where they join into and form the curved section 36 across the outer end or tip of the wall 22 which forms the toe portion T. The flange sections 34, 35 and 36 are of less width than the width of the sections 32 and 33 and are formed from and integral with the opposite side walls 20 and 23 and around the curved tip of wall 23 at an angle of approximately 90° to the general plane of such walls, so that, the under side of these flanges provide a generally flat seating surface at the under side of the toe portion T and ball portion B of the shoe form F. The edge portion formed between flange sections 34, 35 and 36 and the walls with which such sections are integral is preferably formed with the outer surface transversely rounded, as will be clear by reference to the drawings.

The display shoe form F designed and constructed as hereinabove described to provide the thin walled, one-piece seamless and hollow structure, is formed of a cellulose acetate plastic with the walls thereof having a thickness of the order of approximately .065 of an inch, thus making for lightness and resiliency while retaining the requisite structural strength due to the construction of the form and its one-piece, seamless character. Preferably, as in the example hereof, the wall thickness may be reduced to the order of .05 of an inch along the area which joins the major walls of the form with the continuous flange 30 around the open under or bottom side of the form. In this instance, the widths of flange sections 34, 35 and 36 may be taken to be approximately $\frac{1}{8}$ of an inch, while the width of the sections 31, 32 and 33 may be taken to be approximately $\frac{1}{2}$ inch from

their lower, inner seating edges to the area from which the generation of the inward bending or curvature of these flanges from the main wall structures takes place. Thus, it will be noted that the sections 31, 32 and 33 present, in effect, lower edge seating surfaces which are considerably less in width than the width of the seating surfaces provided by the flanges 34, 35 and 36. Due to the one-piece, seamless construction of the shoe form F, it is possible to provide the form with the continuous flange 30 around the open under or bottom side thereof, as of relatively narrow maximum widths which is a substantial advantage in the molding of the form, as well as to the inherent resiliency and light weight of the form.

The shoe form F thus constructed is capable of being compressed laterally, particularly across the ball portion B thereof, by applying pressures acting inwardly at the opposite sides of such portion to thus bend the side portions slightly inwardly toward each other to reduce the width of the ball portion and place the same under compression. This bending or compressing action takes place when the form is inserted in a shoe of the range of sizes for which the particular form is designed and dimensioned. However, experience has demonstrated that with a plastic form, after a period of use under the heat conditions to which such forms are usually subjected, the form has a tendency to collapse to the shape of the shoe in which it has been inserted and to remain in such collapsed shape when removed from the shoe. When this occurs the form thus loses its originally molded shape and thereafter will not provide the proper fit for effective display of shoes of the sizes for which the form was designed.

We have provided for overcoming the tendency of a plastic shoe form to fail to restore to originally molded shape after compression thereof in a shoe, through the medium of an auxiliary or booster spring unit for augmenting the inherent resiliency of the form that normally reacts to restore the form from compressed condition. In the particular example hereof such spring means takes the form of an expansion spring unit 40 preferably formed of spring wire having an external diameter not to exceed the width of flange sections 34, 35 and 36. The spring unit 40 is bent into a general U-shape to conform to the shape and general contour presented by the inner surfaces of wall 22 around and surrounding the flange sections 34, 35 and 36. In the form of the spring unit 40 of this example, the unit comprises a short leg 41 and a longer leg 42 connected and joined by a curved base or head 43. This spring unit 40 is adapted to be mounted in position at and around the inner sides of the flange sections 33, 34 and 35, with the curved head 43 thereof engaged under the flange 35 and extending around and conforming to the curvature of the inner surface of the tip of the wall 22 which provides the toe portion T.

In order to retain the spring unit 40 in mounted, assembled position against inadvertent displacement, we have molded integrally with the form at opposite side locations on the interior thereof, the lugs or ribs 44 and 45. Rib 44 is located in generally vertically disposed position at or adjacent the inner end of the outer section 33 of flange 30. Rib 44 extends inwardly from the inner side of the outer side wall 20 immediately adjacent to the flange section 33, being in

this particular example joined with the flange section. Rib 45 is located in vertically disposed position at or adjacent the inner end of the inner side flange section 32, and extends inwardly from the inner side of the inner side wall 23 immediately adjacent the flange section 32. Rib 45 is extended to and joins flange section 32, in this instance. Rib 44 is located inwardly from the tip of the toe portion T a greater distance than the spacing inwardly of rib 45 from such tip. The greater spacing inwardly of rib 44 is to accommodate the long leg 42 of spring unit 40 in mounted position at that unit.

The spring unit 40 may be readily inserted and snapped into assembled position in the shoe form with the end of long leg 42 engaged and abutting against the forward side of rib 44 and the end of the short leg 41 being engaged and abutting against the rib 44. Preferably the spring unit 40 is placed under at least slight compression at its inner free ends when in assembled position, if only to assist in retaining the unit against inadvertent displacement. However, if desired, the legs of the spring unit may be spread a sufficient distance apart to place the unit under substantial compression when in seated, assembled position. It is to be particularly noted that when in assembled position in a shoe form F, the spring unit 40 is located completely over and around flange sections 33, 34 and 35, with such sections and the wall 22 of the toe portion T forming a housing for the unit. In this manner the spring unit is maintained against displacement and is positioned against interfering engagement with either the hand or fingers in inserting and removing the shoe form into and from a shoe, or with structure of the shoe during such operations.

We have thus provided as a new article of manufacture, a one-piece hollow, thin walled and resiliency plastic shoe form which is without seams or joints. Because of such one-piece, seamless construction the shoe form lends itself to production in clear, transparent and colorless plastic, or to various colors and shades thereof of transparent or semi-transparent character. However, due to the design and construction of the shoe form F, and particularly to the fact that the width and length dimensions of the opening surrounded by the inner edge of the continuous flange 30, are less at every location thereon, than the width and length dimensions of the interior of the form immediately adjacent such flange, the molding of such form presents certain serious and difficult problems. We have overcome these problems by the design, construction and functioning of an injection molding apparatus which forms a part of our present invention and which is described and explained in detail hereinafter.

It will also be evident that various other changes, various eliminations, substitutions and additions may be resorted to without departing from the broad spirit and scope of our invention and, hence, we do not desire or intend to limit our invention in all respects to the particular example thereof herein disclosed, except as may be required by intended limitations thereto appearing in the appended claims.

What we claim is:

1. As a new article of manufacture, a shoe display form comprised of a one-piece, thin-walled, seamless hollow body structure molded from a thermoplastic material; said body structure providing a foot portion including a toe portion and

a heel portion; said body structure being closed at the top side thereof by a wall integral therewith and disposed transversely thereacross in continuous integral jointure with said body structure; said body structure being open at the bottom side thereof and being formed with an inturned flange integral therewith and extended around the open bottom side thereof; and said flange around the heel portion of said body structure being curved inwardly on a radius of curvature greater than the radius of curvature of said inturned flange around said toe portion.

2. As a new article of manufacture, a shoe display form comprised of a one-piece, thin-walled, seamless hollow body structure molded from a thermoplastic material; said body structure providing a foot portion including a toe portion, a heel portion and an intermediate portion therebetween; said body structure being closed at the top side thereof by a wall integral therewith and disposed transversely thereacross; said body structure being open at the bottom side thereof and being formed with an inturned, seamless flange integral therewith and extended around said open bottom side; said flange around the heel portion and along the opposite sides of said intermediate portion of said body structure being curved inwardly on a radius of curvature greater than the radius of curvature of said inturned flange around and along the opposite sides of said toe portion; the inturned flange along one side of said toe portion being of greater length than the portion of said flange along the opposite side of the toe portion; and the flange portions along

opposite sides of the toe portion joining and merging uninterruptedly into and integrally with the adjacent ends of the portions of the flange at opposite sides of the intermediate portion of said body structure.
